APPARATUS FOR CLEANING BOTTLES

James L. Herold and Joseph W. Dawson, St. Louis, Mo., assignors to Barry-Wehmiller Machinery Company, St. Louis, Mo., a corporation of Missouri

Application March 5, 1929, Serial No. 344,202

10 Claims. (Cl. 15—61)

This invention relates to apparatus for cleaning bottles. One of the objects is to thoroughly cleanse the bottles in a relatively small and compact unitary apparatus adapted to perform successive cleaning operations that have heretofore required the use of several large and expensive machines. In addition to greatly reducing the cost of the equipment, and also reducing the space occupied thereby, we have shown how the several 5 cleansing operations may be easily and quickly carried out with the aid of a single operator instead of several operators.

The invention includes certain combinations of features contributing to the above mentioned results, as well as novel details which may be advantageously employed either alone, or in combination with some or all of the other features.

More specifically stated, an object is to subject the bottles to successive soaping operations in 10 different liquids, with intervening or additional cleaning operations so performed that the effect of the soaping is immediately supplemented by other operations that become most effective, and relatively inexpensive, when performed with the soaking operations.

To aid in describing a specific form of the invention, we will now briefly refer to a series of operations that may be carried out in the system shown by the accompanying drawings, but it is to 15 be understood that the scope of the invention will be defined by the terms of the claims.

The bottles may be fed into one end of the machine and eventually discharged at the same end where they are under the observation and control of a single operator. Some of the operations may be performed while the bottles are traveling away from said end, and others are most advantageously performed while the bottles 20 are returning to the same end.

Four major bottle cleaning principles may be carried out by first subjecting the bottles to a presoaking and preheating while they travel 25 through a body of warm liquid; second, transmitting the bottles through a body of hotter liquid, preferably a hot chemical solution; third, forcibly projecting streams of liquid onto the bottles immediately after they leave the chemical solution; fourth, forcibly brushing the bottles after they 30 pass from said streams.

More specifically stated, the particular system hereafter described subjects the bottles to two submerged soaking operations in different liquids while they slowly travel away from one end of the apparatus, and thereafter, while the bottles 35 are returning to said end, they are forcibly washed

and then slowly passed through a soaking liquid to a brushing device which acts upon some of the soaking liquid while forcibly brushing the bottles, and this is followed by a cleansing both inside and outside derived from forcible streams of clean liquid. 5

By successively performing these operations, without any substantial intervening lapse of time, there is an important coaction in the several operations. The bottles arrive at each station at the 10 desired temperature and in condition for the operation to be performed there, and they leave each station in a condition that enables them to most effectively receive the next operation. Moreover, owing to the peculiar arrangement of 15 the series of stations, several of the operations can be properly and easily performed in a small portion of the apparatus while the bottles are returning to the operator's station.

With the foregoing and other objects in view, 20 the invention comprises the novel construction, combination and arrangement of parts herein-after more specifically described and illustrated in the accompanying drawings, wherein is shown the preferred embodiment of the invention. 25 However, it is to be understood that the invention comprehends changes, variations and modifications which come within the scope of the claims hereunto appended.

Fig. 1 is a side elevation of an apparatus embodying the features of this invention. 30

Fig. 2 is a longitudinal section of the same, with some of the parts shown diagrammatically.

Fig. 3 is a section on a larger scale showing one of the bottle holders and a brush in the bottle. 35

Fig. 4 is a detail view showing how the bottles discharge their contents after leaving the brushing device.

Fig. 5 is a vertical section showing portions of the washing and wiping device adapted to 40 discharge streams of chemical solution into the bottles.

Fig. 6 is an enlarged top view of the rotary nozzle shown in Fig. 5, the wiper being omitted.

Fig. 7 is an enlarged vertical section of the 45 rotary nozzle.

Fig. 8 is a top view showing how streams of cleansing liquid are utilized to rotate the bottles.

Fig. 9 illustrates a bottle in one of the bottle 50 holders, and a spindle which is moved upwardly to lift and rotatably support the bottle while it is subjected to the streams of liquid.

To illustrate one form of the invention, we have shown an apparatus comprising an elongated housing provided with an endless bottle- 55

carrier including endless chains 1, shown diagrammatically in Figures 1 and 2, and bottle holders 2 carried by said chains. It is to be understood that any suitable power mechanism (not shown) may be employed to impart an intermittent movement to the bottle-carrier, so that the bottles will move step by step, as is usual in this art, and that any suitable supports may be employed to guide the bottle-carrier in the endless course herein shown. We have omitted some of the structural details as they are not necessary to an understanding of the invention.

The bottles enter the front end of the machine by passing over a curved guide 3 at the left of Fig. 2, and after making a complete circuit through all of the stations, the bottles are discharged at the same end of the machine by passing onto an inclined guide 4, which lies immediately above the guide 3, as shown in Fig. 2.

The bottles may be forcibly discharged onto said guide 4 by means of an arm 5, pivotally supported at 6, and having an extension 7 adapted to enter the bottle holders to discharge the bottles therefrom. The guide 4 is pivoted at 8, so it can be shifted to move the bottles to the upright position shown at B' in Fig. 2.

The endless bottle-carrier travels in the direction indicated by arrows in Fig. 2. It moves downwardly from the inlet guide 3 and passes through a preliminary soaking compartment 9, preferably containing relatively fresh water wherein the bottles are submerged as they travel over a stationary plate 10 which confines the bottles in the bottle holders.

The bottle-carrier moves upwardly from the compartment 9, passes around a rotary member 11, and thence downwardly into the liquid in an intermediate soaking compartment 12. A closed hood 13 (Fig. 2) extends from the liquid in the preliminary compartment 9 to the liquid in the intermediate compartment 12, the lower ends of said hood 13 being extended into the respective liquids to form liquid seals, whereby vapor is confined in the hood. Therefore, as the bottles slowly travel from one of said liquids to the other, they are "soaked" in a body of warm vapor which extends from one body of liquid to the other. The bottles then travel slowly through the elongated soaking compartment 12 which preferably contains a chemical solution, such as caustic soda, wherein the bottles are submerged. At this time, the bottles are confined in the holders by means of a plate 14. They travel approximately from end to end of this long compartment 12 and then rise at the rear portion of the apparatus, where the bottle-carrier is guided upwardly in an inclined course and then turned over a rotary device 15 (Fig. 2) to discharge the liquid contents of the bottles onto the bottles in said inclined course, thereby producing a shower which aids in cleaning the rising bottles. It will be noted that the bottles are inverted as the bottle-carrier passes over the rotary device 15.

The inverted bottles then begin their return movement at a high elevation, and in a horizontal course, above the liquid in the compartment 12.

A closed hood 16 at the rear of the machine (Fig. 2) extends from the liquid in the soaking compartment 12 to the liquid in another soaking compartment 17 to confine the vapors which rise from these liquids, so the bottles are again subjected to a "vapor soak" at the beginning of their movement toward the front of the machine, and this action continues from the time the bottles

leave the liquid in compartment 12 until they enter the liquid in compartment 17.

While the bottles are in the upper portion of the hood 16, they are acted upon by streams of liquid which forcibly cleanse the inner and outer faces of the bottles in a peculiar manner which will be hereafter described. At this time the bottles are inverted, so the washing liquid, preferably a chemical solution will drain into the compartment 12, instead of passing into the compartment 17.

The compartment 17 contains relatively fresh water, and the bottle-carrier passes downwardly into this liquid at one side of the vapor seal 18, and then upwardly from the surface of the liquid at the opposite side of said compartment. At this opposite side, the rising bottle holders are approximately horizontal, so the bottles B carry water from the soaking compartment 17, as shown in Fig. 3. The bottles are then acted upon by a brushing device shown diagrammatically in Figures 1, 2 and 3. This brushing device is claimed and more fully illustrated in an application for patent filed by us on June 27, 1929, Serial Number 374,035, which has matured into Patent No. 1,950,146, granted March 6, 1934. The brushing device comprises a housing 19 slidable on a horizontal guide 20, and horizontal spindles 21 extending from said housing and adapted to enter the bottles as shown most clearly in Fig. 3, each spindle being provided with a brush 22. The spindles may be rotated by gearing in any suitable manner (not shown) and the power for this rotary movement may be derived from a pulley 23 on the housing 19, and a belt 24 to drive said pulley.

The housing 19 is moved horizontally on the guide 20, so as to move the rotating brush spindles 21 into and out of the bottles while the bottle-carrier is at rest.

Abutments 25 (Figures 2 and 3) prevent longitudinal displacement of the bottles during the brushing operations. It will be noted that there are two of these brushing devices 21, one above the other, so each bottle is subjected to two brushing operations. At this time, the horizontal bottles contain water which they carried from the compartment 17, and it is not necessary to supply water through the brush spindles.

The bottle-carrier moves upwardly from the brushing device, and then turns to the left as indicated by arrows in Fig. 2, as it starts on a long horizontal course toward the front of the machine. As the bottles turn into this horizontal course, they are tilted to discharge the liquid which remains in the bottles after the brushing operation. However, before they are tilted the bottles pass a yielding deflector 26 (Figures 2 and 4), preferably a rubber flap extending from a trough 27, the object being to deflect the water into this trough. Some of the water passing from the bottles is discharged onto this flap 26, and some is discharged directly into the trough 27.

The empty bottles then travel horizontally between an upper horizontal pipe 28 and a pair of lower pipes 29, as shown in Figure 2. The upper pipe 28 discharges streams of fresh cleaning water onto the bottles to wash the outer faces, and the lower pipes discharge streams of fresh water into the bottles to cleanse their inner faces. As the inverted bottles continue their forward movement in the long horizontal upper course, they pass over a pair of pipes 30 (Fig. 2) which may be used if desired to discharge hot sterilizing water, or chlorine, in the bottles.

The inverted bottles are then drained and dried as they travel to the front of the machine where the carrier moves downwardly to the discharge device 7 which pushes the bottles from the 5 holders and onto the guide 4, as previously described.

We will now refer to the washing operations which occur in the upper portion of the hood 16 (Fig. 2) when the bottles are inverted in passing from the soaking compartment 12 to the soaking compartment 17.

A pair of horizontal pipes 31 is located above the course of the bottle-carrier, as shown in Figures 1, 2, 8 and 9, and these pipes have nozzles 32 arranged as shown in Fig. 8 to discharge streams of liquid onto the peripheral faces of the bottles. The streams are projected from the nozzles 32 in lines at angles to the axis of the bottle, and we will show how the bottle is rotated in response 20 to the energy derived from these streams which act upon the periphery of the bottle. This feature is claimed in an application for patent filed by us on December 5, 1928, Serial Number 324,- 005, Patent No. 1,824,993 issued on September 25, 1931.

Fig. 9 shows that the bottom of an inverted bottle may be cleansed by these streams when the bottle is in one of the bottle holders 2, and in the upper right hand portion of Fig. 2 we have 30 shown how the bottle B may occupy an elevated position directly between the streams which rotate the bottle as it moves upwardly and downwardly relative to the bottle holder.

The means for raising and lowering the bottles between said streams comprises a spindle 33 (Figures 2 and 9) adapted to lie entirely below the bottle as shown in Fig. 9, and adapted to occupy the elevated position shown in Fig. 2. Any suitable means (not shown) may be employed to raise and lower the spindle 33.

A cap 34, rotatably mounted on the upper end of said spindle 33, has a pointed top adapted to enter the bottle, and a flange 35 (Fig. 9) adapted to form a seat for the lower portion of the 45 bottle.

The spindle 33 is moved upwardly to lift the bottles from the position shown in Fig. 9 to the position shown in Fig. 2, and then moved downwardly to replace the bottle in the holder. The 50 bottle is free to rotate with the cap 34 at the top of the spindle 33, and it is rotated by the power derived from the streams of liquid issuing from the nozzles 32, thereby forcibly cleansing the entire outer face of the bottle. These 55 streams of liquid are preferably obtained from the chemical solution in the compartment 12, as will be hereafter described.

After leaving this cleansing station, the bottles pass to an adjacent station where their inner faces are forcibly cleansed by streams of liquid and at the same time forcibly wiped. In performing this double operation, we preferably employ vertical spindles 36 (Figures 1, 2 and 5) carried by horizontal pipes 37 which may be raised and lowered by any suitable mechanism (not shown). This washing and wiping device is claimed in an application for patent on Nozzles filed by William Schuchardt and James L. Herold on May 9, 1928, Serial Number 276,237, 65 Patent No. 1,850,570, issued on March 22, 1932. However, said device may be employed to perform one of the operations in the present invention. Each spindle 36 of this device is in the form of a vertical tube through which liquid is 70 discharged from a horizontal pipe 37. The up-

per end of each spindle 36 is provided with a nozzle 38 screwed onto a short tube 39 (Fig. 7) having a flange 40 at the bottom. An anti-friction collar 41 is interposed between said flange 40 and the bottom of a member 42 which is 5 screwed into the spindle 36. The nozzle 38 and tube 39 (Fig. 7) are therefore free to rotate on the spindle 36.

The nozzle 38 is provided with tangential discharge passages 43 (Figures 6 and 7) through 10 which streams of liquid are forcibly discharged with the result of rotating the nozzle. These forcible streams are distributed over the inner face of the bottle as the spindle 36 moves upwardly from the position shown by dotted lines 15 in Fig. 5 and then downwardly to said position.

A flexible wiper 44 (Figures 5 and 7) is secured in a slot at the upper end of the nozzle 38 and this wiper rotates with the nozzle to forcibly wipe the inner face of the bottle. The 20 liquid discharged through the nozzle 38 is preferably derived from the chemical solution in the compartment 12, as will be hereafter described, so the bottles are subjected to the cleansing action of the chemical solution and at the same 25 time forcibly wiped by the rotating wiper 44. A very thorough cleansing operation is thus performed in a novel manner.

It will now be understood that the inverted bottles in the upper portion of the hood 16 at 30 the rear of the machine are forcibly cleansed, first by a device acting upon the outer faces of the bottles, and then by a pair of devices which act successively on the inner faces of the bottles, the liquid used in these operations being derived 35 from the compartment 12.

We will now describe a suitable means for delivering and circulating the liquids in the apparatus.

Fig. 1 shows a fresh water supply pipe 45 40 provided with valves 46 and 47. This supply pipe has branches 48 and 49 at its lower end. The branch 48 includes a valve 50, and this branch terminates at 51 in the preliminary soaking compartment 9. The branch 49 is provided with valves 52 and 53, and it leads to the fresh water 45 soaking compartment 17, as indicated at 54 in Fig. 1. A pipe 55 extends downwardly from the branch pipe 49 to the intermediate compartment 12. The valves referred to may be positioned to supply fresh water to the various compartments before the system is placed in service. 50

The fresh water pipe 45 (Fig. 1) is also provided with a branch 56 leading to the discharge pipe 28 above the course of bottles, and also to 55 the pair of discharge pipes 29 immediately below said course.

Valves 57 in this branch may be operated in any suitable manner to control the discharge of fresh water through the pipes 28 and 29. When 60 the system is in operation, water overflows from the fresh water compartment 17 to the preliminary compartment 9 by passing through an overflow pipe 58 (Fig. 1) and then through the pipes 49 and 48 to the compartment 9, the valves being 65 then positioned to provide for this overflow. The other overflow (Fig. 1) includes a pipe 59 leading from the preliminary compartment 9, and a pipe 60 leading from the intermediate compartment 12. 70

The trough 27, which receives the water discharged from the brushed bottles, has an overflow 61 (Fig. 1) leading to the pipe 49 whereby this water is conducted to the pipe 48 and then 75 into the preliminary compartment 9.

A pan 62 (Figures 1 and 2) receives fresh water drained from the bottles during the final washing operations. This pan (Fig. 1) discharges its contents through a tube 63 and a pipe 64 leading to the compartment 17.

We will now refer to a means for transmitting chemical solution from the compartment 12 to the discharge pipes 31 and 37 in the upper portion of the hood 16 at the rear of the apparatus. A pipe 65 (Fig. 1) leads from the forward end portion of the compartment 12 to a pump 66 having a discharge pipe 67 leading to the pair of pipes 31. A branch 68, extending from the pipe 67, leads to flexible tubes 69 (Fig.

15) and these tubes are connected to the pipes 37. Strainers 70 (Fig. 2) are located in the course of the chemical solution flowing to the pipe 65.

We gradually increase and then gradually decrease the temperature of the bottles. The desired temperatures may be obtained in starting the system by means of steam coils 71 located in the compartments 9, 12 and 17, as shown in Fig. 2, said coils being supplied with steam through the medium of pipes 72, shown in Fig. 1.

25 Before the system is placed in service, the steam may be regulated to obtain a high temperature in the compartment 12 and lower temperature in the compartments 9 and 17.

However, when the system is in operation, 30 there is a heat exchange which automatically tends to maintain the desired variation in the temperatures. The highest temperature is in the chemical solution in the long compartment 12. The delivery of steam to this compartment 35 may be regulated to maintain the desired maximum temperature, and heat will then be transmitted from the chemical solution to provide the gradual increase and gradual decrease in the temperature of the bottles.

40 The hot liquid in the long compartment 12 contacts with the partition wall 73 at the forward end of said compartment so as to transmit heat to the presoaking and preheating compartment 9 which lies at a point remote from the heating coil 71 in the long compartment 12, so there is a very gradual increase in the temperature of the bottles as they pass through the compartment 9 and enter the long compartment 12. This gradual increase in temperature continues 50 as the bottles approach the heating coil 71 in the long compartment 12.

The temperature decreases as the bottles rise from the hot chemical solution at the rear of the apparatus, and this gradual decrease continues 55 as the bottles are acted upon by the streams from the pipes 31 and 37, said streams being transmitted from the relatively cool forward end of the long compartment 12.

60 The bottom and one side wall of the fresh water compartment 17 contacts with the hot liquid in the long compartment 12, so the fresh water is maintained at the desired lower degree of temperature by the transmission of heat through said bottom and side wall. The warmest portion 65 of the body of fresh water lies at the points where the bottles enter said water. The final cooling occurs at the streams of fresh water which strike the bottles after they leave the brushing device.

70 An important factor of the heat exchange lies in the constant transfer of heat from the bottles and bottle carrier to the liquid in the compartment 17. After being heated by the hot liquid in compartment 12, the bottles and their holders 75 pass through the vapor in hood 16 and enter the

liquid in compartment 17. Heat is thus transmitted to the body of liquid in compartment 17 which receives cool fresh water from the final rinsing pan 62. This constant heating and cooling maintains the body of liquid in 17 at temperatures between the two extremes, the temperature being relatively high at the point where the bottles enter this body of liquid, and somewhat cooler where they leave it, but the conditions are constant, and the desired gradual cooling of the 10 bottles is accomplished in a simple manner by utilizing the heat of the bottles and bottle carrier for one extreme, while adding cool water for the other extreme.

The resultant liquid has a substantially constant average temperature between the two extremes, and it overflows from the compartment 17 to the preliminary compartment 9 where a similar heat exchange takes place.

The relatively warm, or moderated, liquid 20 which enters the compartment 9, transfers some of its heat to the cold bottles and bottle carriers. The average temperature in this compartment 9 bears a fixed relation to the low temperature of the cool incoming bottles and the higher temperature in the adjoining compartment 12; but there is a constant blending of the warm and cool portions of the liquid, and a very gradual increase in the temperature of the bottles as they 25 pass through this liquid.

30 It will now be readily understood that the unitary system herein disclosed is adapted to very gradually increase and then gradually decrease the temperature of the bottles, so as to avoid breakage while the following successive operations are performed.

The bottles travel through a continuous series of bodies in contact with each other as follows:

First, through the preheating and presoaking liquid in the compartment 9 where the bottles 40 are submerged; second, through a confined body of vapor in the hood 13 extending from said liquid to the hot chemical solution in compartment 12; third, through said hot chemical solution in which they are submerged; fourth, 45 through the confined body of vapor in the hood 16 which extends from the chemical solution to the water in the compartment 17, and fifth, through the body of fresh water in the compartment 17. Some of the treatments occur while the bottles 50 are traveling away from the front of the machine, and other operations are performed during the return trip.

55 At the beginning of the return trip, the inner and outer faces of the bottles are forcibly acted upon by the streams of liquid discharged from the pipes 31 and 37, near the rear of the machine, and the bottles then travel through the fresh water compartment to the brushing device which acts upon some of this relatively fresh water while brushing the bottles. The final cleansing operations are then performed by streams of fresh water discharged from the pipes 28 and 29 to the inner and outer faces of the bottles. If desired, a sterilizing liquid could be 60 discharged from the pipes 30. Ample time for draining and drying is then allowed before the bottles reach the discharge device 7 at the front of the machine.

70 We claim:

1. In a bottle cleaning apparatus, a preliminary soaking compartment adapted to contain warm liquid, an intermediate soaking compartment adapted to contain a liquid at a higher temperature, another soaking compartment 75

- adapted to contain liquid at a temperature lower than that of the intermediate compartment, an endless bottle-carrier traveling through said compartments in the order named to subject the 5 bottles to successive soaking operations while gradually increasing and then gradually decreasing the temperature of the bottles, the last mentioned soaking compartment having its bottom wall and one of its side walls in contact with the 10 hot liquid in said intermediate compartment, said intermediate compartment being provided with a wall contacting with the hot liquid therein and also with the relatively cool liquid in said preliminary soaking compartment, so as to transfer 15 heat from the hottest liquid to the cooler liquid in said preliminary soaking compartment, and means for heating the liquid in said intermediate compartment to maintain the desired temperatures.
- 20 2. In a bottle cleaning apparatus, a preliminary soaking compartment adapted to contain warm liquid, an intermediate soaking compartment adapted to contain a chemical solution at a higher temperature, a final soaking compartment adapted to contain water at a temperature lower than that of the chemical solution, a bottle-carrier traveling through said compartments in the order named to subject the bottles to successive soaking operations, a hood extending from 25 the liquid in the preliminary soaking compartment to the solution in said intermediate compartment to confine the vapors in the course of the bottles from the preliminary to the intermediate compartment, a hood extending from the 30 liquid in said intermediate compartment to the liquid in said final compartment to confine the vapors in the course of the bottles from the intermediate to the final soaking compartment, a discharge device whereby streams of the chemical 35 solution from said intermediate compartment are forcibly projected onto the outer faces of the bottles in the last mentioned hood, a second discharge device whereby streams of the chemical solution from said intermediate compartment are 40 forcibly projected onto the inner faces of the bottles in the last mentioned hood, said second discharge device including a rotary wiper acting on the inner faces of the bottles; a pair of brushing devices movable into and out of the bottles 45 at points beyond said final soaking compartment, and means whereby streams of liquid are projected onto the bottles at points beyond said brushing devices.
- 50 3. In a bottle cleansing apparatus, a soaking tank adapted to contain a hot chemical solution, an endless bottle carrier traveling through said solution and above said solution, means for heating the liquid in said soaking tank, said means being remote from the place where the bottle carrier enters said solution, a discharge device arranged above said solution and adapted to forcibly discharge streams of liquid onto the bottles, and means whereby a stream of hot chemical 55 solution is withdrawn from said tank near the portion thereof where the bottle carrier enters said solution and then forcibly projected from said discharge device onto said bottles.
- 60 4. In a bottle cleaning apparatus, a preliminary soaking compartment, an intermediate soaking compartment adapted to contain a hot chemical solution, another soaking compartment higher than said preliminary and intermediate soaking compartments, said other soaking compartment having a bottom wall directly above and adjacent 65 to said intermediate soaking compartment so as to provide for the transmission of heat from said intermediate soaking compartment, through said bottom wall and thence into said other soaking compartment, and an endless bottle-carrier traveling through said preliminary and intermediate compartments at a relatively low elevation and returning through the other soaking compartment at a higher elevation.
- 70 5. In a bottle cleaning apparatus, a preliminary soaking compartment, an intermediate soaking compartment adapted to contain a hot chemical solution, another soaking compartment higher than said preliminary and intermediate soaking compartments, said other soaking compartment having a bottom wall directly above and adjacent 75 to said intermediate soaking compartment so as to provide for the transmission of heat from said intermediate soaking compartment, through said bottom wall and thence into said other soaking compartment, and an endless bottle-carrier traveling through said preliminary and intermediate compartments at a relatively low elevation and returning through the other soaking compartment at a higher elevation.
- 80 6. In a bottle cleaning apparatus, a preliminary soaking compartment adapted to contain warm liquid, an intermediate soaking compartment adapted to contain a chemical solution at a higher temperature, another soaking compartment adapted to contain liquid at a temperature lower than that of the chemical solution, and an endless bottle-carrier traveling through said compartments in the order named to subject the bottles to successive soaking operations while gradually increasing and then gradually decreasing the temperature of the bottles, a discharge device above the hot solution in said intermediate compartment adapted to discharge streams of liquid on the bottles leaving said solution, said intermediate soaking compartment being provided with a heating element remote from the portion thereof where the bottle carrier enters said intermediate soaking compartment, and means whereby the hot solution is withdrawn from said intermediate compartment near the portion thereof where the bottle carrier enters said intermediate compartment and forced through said discharge device so as to gradually cool the bottles leaving said intermediate soaking compartment.
- 85 7. In a bottle cleaning apparatus, a bottle-carrier movable in an endless course and provided with inlet and discharge devices at one end of the apparatus so as to receive and discharge the bottles at the same end, a preliminary soaking compartment and an intermediate soaking compartment through which the bottle carrier passes while traveling away from said end, another soaking compartment higher than said preliminary soaking compartment and said intermediate soaking compartment through which said carrier travels while returning to said end, the bottom of said higher soaking compartment being directly above and adjacent to said intermediate soaking compartment to provide for the transfer of heat from said intermediate soaking compartment to said higher soaking compartment, said higher soaking compartment being provided with an overflow leading to one of said other compartments.
- 90 8. In a bottle cleaning apparatus, a preliminary

- nary soaking compartment adapted to contain warm liquid, an intermediate soaking compartment adapted to contain a liquid at a higher temperature, a relatively clean soaking compartment 5 adapted to contain water at a temperature lower than that of the intermediate compartment, a bottle-carrier traveling through said compartments in the order named to subject the bottles to successive soaking operations, a discharge device whereby streams of liquid are forcibly projected onto the outer faces of the bottles passing from said intermediate to said relatively clean compartment, a second discharge device whereby streams of liquid are forcibly projected onto the 10 inner faces of the bottles passing from said intermediate to said relatively clean compartment, means whereby liquid is withdrawn from said intermediate compartment and forcibly transmitted to said discharge devices, said second discharge 15 device including a rotary wiper acting on the inner faces of the bottles; a brushing device movable into and out of the bottles at points beyond said relatively clean soaking compartment, and means whereby streams of liquid are projected 20 onto the bottles at points beyond said brushing devices.
9. In a bottle cleaning apparatus, a soaking tank, a bottle carrier movable through said soaking tank and adapted to carry the bottles upward- 25 ly therefrom in positions wherein liquid from

the soaking tank is retained in the bottles, a brushing device movable into the bottles containing said liquid, means whereby the bottles are tilted beyond said brushing device to discharge said liquid, and means for transmitting said liquid to said tank, said means including a deflector in the course of the bottles adapted to deflect the liquid discharged therefrom, said deflector being yieldable to permit the bottles to pass the deflector. 5

10. In a bottle cleaning apparatus, a preliminary soaking compartment adapted to contain warm liquid, an intermediate soaking compartment adapted to contain a liquid at a higher temperature, another soaking compartment adapted to contain liquid at a temperature lower than that of the intermediate compartment, and an endless bottle-carrier traveling through said compartments in the order named to subject the bottles to successive soaking operations while 15 gradually increasing and then gradually decreasing the temperature of the bottles, the last mentioned compartment being directly above and adjacent to said intermediate compartment and in heat transferring relation thereto and at a higher elevation than said preliminary soaking compartment and provided with an overflow leading to said preliminary soaking compartment. 20

JAMES L. HEROLD.

JOSEPH W. DAWSON. 30
